(57) **CLAIM**

The ornamental design for a display panel for an ice maker, as shown and described.

DESCRIPTION

FIG. 1 is a perspective view of a display panel for an ice maker installed on one type of ice maker;

FIG. 2 is a perspective view of the display panel for an ice maker with the environment removed for ease of illustration;

FIG. 3 is a front view thereof;

FIG. 4 is a right side view thereof;

FIG. 5 is a top view thereof;

FIG. 6 is a left side view thereof; and,

FIG. 7 is a bottom view thereof.

The rear of the display panel for an ice maker forms no part of the claimed design. The broken lines in the drawings depict portions of the display panel for an ice maker that form no part of the claimed design. The additional sets of broken lines in FIGS. 1-2, showing ice makers, represent environment and form no part thereof.
